UNITED STATES PATENT OFFICE.

ALBERT J. HORTON, OF WHITE PLAINS, NEW YORK, ASSIGNOR TO THE CUTLER-HAMMER MFG. CO., OF MILWAUKEE, WISCONSIN, A CORPORATION OF WISCONSIN.

MOTOR-CONTROLLER.

1,019,045.

Specification of Letters Patent.

Patented Mar. 5, 1912.

Application filed May 4, 1908. Serial No. 430,828.

To all whom it may concern:

Be it known that I, ALBERT J. HORTON, a citizen of the United States, residing at White Plains, in the county of Westchester 5 and State of New York, have invented new and useful Improvements in Motor-Controllers, of which the following is a full, clear, concise, and exact description, reference being had to the accompanying drawing, forming a part of this specification.

My invention relates to improvements in controllers for electric motors, and more particularly to automatic starting devices therefor.

15 Broadly, my invention comprehends the employment of a single electroresponsive device for successively actuating a number of resistance switches to remove a variable starting resistance from the motor circuit gradually and proportionally to the building 20 up in speed of the motor.

In order to more clearly disclose my invention I have illustrated in the accompanying drawings devices embodying my invention.

25 In the accompanying drawings, Figure 1 is a front elevation of a device embodying my invention and showing the circuit arrangement therefor, parts of the device being shown in section. Fig. 2 is a view similar to Fig. 1 illustrating parts of the device in different positions. Fig. 3 illustrates a modified form of device embodying my invention.

35 In the embodiment of my invention illustrated, which is a two-step self-starter, I provide a panel or supporting base A upon which the several parts of the device are mounted. An electromagnetic winding or 40 solenoid B is mounted in a frame B', which is suitably secured to the panel A. The winding B is provided with a plunger C which carries at its lower end a tail rod E, and at its upper end a tail rod D. Both 45 of said tail rods are preferably partially screw-threaded. Internally threaded collars d, d' and d² are fitted onto the screw-threaded portion of the tail rod D and are adjustable thereon. Set screws d³ are provided for locking the collars in position after 50 being adjusted on the rod. Loosely mounted on the tail rod D and interposed between the collars d and d' is a disk D' insulated from said tail rod and adapted to bridge stationary contacts 1 and 2 mounted on the

panel A. A disk D² is loosely mounted on the tail rod D between the collars d' and d², said disk being insulated from the tail rod and being adapted to bridge stationary contacts 3 and 4 mounted on the base A. The 60 disks D' and D² bridge their respective contacts when the plunger is in its lowermost position, as shown in Fig. 1, and in this position the collar d' is at a greater distance from the disk D² than the collar d is from 65 the disk D'. It will thus be seen that when the core is raised the disk D' will be raised from contacts 1 and 2 before the disk D² will be raised from contacts 3 and 4. The purpose of this arrangement will be here- 70 inaftter explained.

Adjustably mounted on the tail rod E, adjacent to its lower end, is a switch e provided with laminated brushes e'-e' adapted to engage flattened surfaces on the underside 75 of stationary contacts 5 and 6, mounted upon the panel A. This switch is insulated from the tail rod E and is supported thereon between nuts e² and a collar e³ threaded onto the tail rod E and provided with a 80 set-screw e⁴. A disk e⁵ is loosely mounted upon the tail rod E and insulated therefrom, said disk being adapted to bridge stationary contacts 7 and 8 mounted upon the panel A. Interposed between the disk e⁵ and a collar 85 e⁶ is a coil spring e⁶. The collar e⁶ is threaded onto the tail rod and adjustable thereon to regulate the tension of the spring e⁶. A set-screw e⁸ is provided for locking the collar e⁶ in position. With this arrangement 90 it will be seen that when the core C is raised the disk e⁵ will bridge contacts 7 and 8 before the switch e will bridge contacts 5 and 6. The purpose of this arrangement will be hereinafter explained. To prevent the tail rod E and switch e from turning, said switch is provided with a projecting pin e⁹ which slides in a groove e¹⁰ formed in an insulating block e¹¹ secured to the base A. The winding B is provided with a stationary plug F, secured to the frame B', for sealing the plunger C in its uppermost position. As shown the plug F is tubular and is provided with a non-magnetic bushing G. Mounted within the plug F and surrounding the tail rod D is a secondary plug H. The plug H is free to slide upon the tail rod D and also within the plug G and is provided at its upper end with an adjustable collar h bearing upon the plug 110

G. By adjusting the collar h the plug H may be raised or lowered in the winding B . In practice the plug H is so adjusted as to seal with the plunger C when raised sufficiently to remove the first step of the starting resistance.

The circuit arrangement for this device is as follows: The main lines 9 and 10 lead from a suitable source of electrical supply 10 and double pole switch L is provided for closing the main circuit. Contact 5 is connected by conductor 11 to the main line 10. Contact 7 is connected by conductor 12 through a resistance 13 to conductor 11. 15 The contacts 7 and 8 are connected through resistance 14 and contact 8 is also connected by conductors 15 and 16 to one terminal of the armature k of the motor K . The other terminal of the armature k is connected to 20 one terminal of the series field winding k' , while the other terminal of the field winding k' is connected by conductor 17 to the main line 9. Contact 6 is connected by conductor 18 to conductor 16. k^2 is a shunt field 25 winding for the motor K connected across the main line by conductors 19 and 20. The winding B is connected across the terminals of the armature k and its circuit may be traced from conductor 16 by conductor 21 30 to contact 4, through resistance 22 to contact 3 and by conductor 23 to contact 1, thence through resistance 24 to contact 2 by conductor 25 through winding B and by conductor 26 to the opposite terminal of the 35 armature k .

In order that the operation of this device may be more thoroughly understood, let it be assumed that the air gap between plunger C and the plug H in the winding B is so 40 arranged that a predetermined potential must exist at the terminals of the winding B before the same will respond to lift the plunger C to bridge the contacts 7 and 8. Let it be further assumed that the tension of 45 the spring e^6 is so regulated that the potential at the terminals of the winding B must be increased a predetermined amount before the plunger C will be raised to bridge the contacts 5 and 6.

50 The following is a description of the operation of this device: Assuming that the switch L is closed and that the plunger C is in its lowermost position, as shown in Fig. 1, current will flow from the main line 10 by conductor 11, through the resistance 13, by conductor 12 to contact 7, through resistance 14 to contact 8, and thence by conductors 15 and 16 through armature k , series field winding k' to conductor 17 and thence 55 to main line 9. Current will also flow from main line 10, by conductor 20, through the shunt field winding k^2 and by conductors 19 and 17 back to the main line 9. The motor is thus started with all of the starting 60 resistance in circuit. Owing to the fact that

there is a large drop in potential across the starting resistance and there is little or no drop across the armature, when the motor is initially started, practically all of the current will flow through the motor armature 70 and little or no current will flow through the winding B when the motor circuit is first closed. Thus when the motor is initially started the potential at the terminals of the winding B is not sufficient to cause said 75 winding to respond. However, as the armature speeds up it generates a counter-electro-motive force which increases proportionally with the building up in speed of the armature. As the counter-electro-motive force 80 increases the drop in the potential across the armature increases, while the drop in potential across the starting resistance decreases which results in an increase in potential at the terminals of the winding B . 85 As soon as a predetermined potential exists at the terminals of the winding B the same will respond and raise the plunger C , causing the disk e^5 to bridge the contacts 7 and 8 and removing the disk from engagement 90 with contacts 1 and 2. Further movement of the plunger at this time is prevented by the action of the spring e^6 . This position of the plunger C is shown in full lines Fig. 2. In 95 this position the plunger C engages with, and is sealed by, the secondary plug H . The advantage of employing the secondary plug is that it decreases the air gap between the plunger C and the plug, and consequently decreases the reluctance of the magnetic circuit, which results in a very strong 100 pull being exerted upon the core C . This causes the disk e^5 to be held firmly against contacts 7 and 8. The use of the secondary plug H also tends to cause a halt in the 105 movement of the plunger C when it engages therewith, as it partially completes the magnetic circuit. Upon further movement of the plunger C it carries the plug H with it. 110 As soon as the disk e^5 bridges the contacts 7 and 8 section 14 of the starting resistance is short-circuited, while the removal of the disk D^2 from the contacts 1 and 2 results in the insertion of resistance 24 in the circuit 115 of the winding B . The motor circuit may now be traced to contact 7, as previously described, thence across disk e^5 to contact 8 and by conductors 15 and 16, through the armature k , and series field winding k' to the opposite side of the main line. The circuit through the winding B may now be traced from contact 4 across the disk D^2 to contact 3, by conductor 23 to contact 1 across 120 resistance 24 to contact 2, and thence through the winding B to the terminal of the armature k . It will thus be seen that more current is now sent through the armature while the flow of current through the winding B is decreased. The plunger C will remain in 125 this position until the armature reaches a 130

predetermined speed when the potential at the terminal of the winding B will be sufficiently increased to cause said winding to overcome the opposition of the spring e^6 and raise the plunger C to the position shown in dotted lines, Fig. 2. In this position of the plunger C contacts 5 and 6 are bridged by the switch e' , while the disk D ^{2} is out of engagement with the contacts 3 and 4. The plunger C engages with and is sealed by the plug F, while the flow of current through the winding B is decreased by the insertion of the resistance 22 to an amount just sufficient to hold the plunger C in its final position. The contacts 5 and 6 being bridged by the switch e' , section 13 of the starting resistance is short-circuited. The motor circuit may now be traced from conductor 11 to contact 5 across switch e' to contact 6, and thence by conductor 16 through the armature k and series field winding k' to the opposite side of the main line. When it is desired to stop the motor the switch L may be opened thus opening the circuit through the motor and also opening the circuit through the winding B, which permits the plunger C to fall, thus inserting the starting resistance in the motor circuit so that the motor cannot be again started until the starting resistance has been inserted in circuit therewith.

It should be understood that by adjusting the collar d^2 on the tail rod D the core C may be raised or lowered in the winding B to vary the air gap between it and the plug G and that by means of this adjustment the device may be set to remove the first step of starting resistance at different predetermined times. Also, that by varying the tension of the spring e^6 the device may be set to remove the second step of starting resistance at predetermined times. Furthermore, it should be understood that additional switches may be carried by the core C for controlling additional sections of the starting resistance and that additional sliding plugs, similar to the plug H, may be employed for sealing the core C upon the removal of each step of starting resistance.

The construction shown in Fig. 3 is similar to that already described, except that in lieu of the switch e a disk M is substituted which is insulated from the tail rod E and resiliently supported thereon by a coil spring M'. When in its lowest position, the disk M engages stationary contacts 27 and 28 mounted upon the base or panel A. Also in this instance instead of mounting two disks upon the tail rod D, only one disk N is mounted thereon, which is adapted to engage stationary contacts 29 and 30, mounted upon the panel A. A collar n adjustably mounted upon the tail rod D is adapted to lift the disk N from the contacts 29 and 30.

The circuit arrangement of this construction

is substantially the same as that already described with the exception that in this instance the conductor 21 extends from conductor 16 to contact 28, through resistance 24 to contact 27 and thence to contact 29, through resistance 22 to contact 30, and thence by conductor 31, through winding B, and conductor 32 to the opposite terminal of armature k . The operation of this device is substantially the same as that already described, for when the plunger C is lifted it brings the disk e^5 into contact with the contacts 7 and 8, thus short circuiting the resistance 14 and at the same time lifts the disk M from the contacts 27 and 28, thus inserting resistance 24 in circuit in series with the winding B, and upon further movement of the plunger the disk M is brought into engagement with contacts 5 and 6, thus short circuiting the resistance 13 and the disk N is lifted by the collar N from the contacts 29 and 30, this inserting the resistance 22 in circuit with the winding B.

Having thus described my invention, what I claim as new and desire to secure by Letters Patent, is:

1. In a controlling device for electric motors, the combination with a resistance, of a plurality of switches for controlling said resistance, an electroresponsive device for closing said switches to gradually remove said resistance from the motor circuit proportionally to the building up in speed of the motor, and means for automatically reducing the flow of current through said electroresponsive device upon closure of one of said switches and further reducing the flow of current through said device upon the closure of another of said switches.

2. In a controlling device for electric motors, the combination with a resistance, of a plurality of switches for controlling the same, an electromagnetic device for successively closing said switches to gradually remove said resistance from the motor circuit proportionally to the building up in speed of the motor, a plurality of sections of resistance adapted to be inserted in circuit with said electromagnetic device and means for inserting one of said sections of resistance in circuit upon the closure of each of said switches.

3. In a controlling device for electric motors, the combination with a plurality of sections of resistance, of a plurality of switches for controlling the same, an electroresponsive device for closing said switches successively to gradually remove said sections of resistance proportionally to the building up in speed of the motor, means for automatically reducing the amount of current flowing through said electroresponsive device upon the closure of one of said switches and further reducing the flow of current therethrough upon closure of an

- controlled by said switches, said winding being adapted to operate said plunger to close said switches successively and at predetermined speeds of the motor, other switches carried by said plunger and arranged to be operated successively, sections of resistance controlled by said latter switches adapted to be inserted in circuit with said winding when said latter switches are operated.
13. In a controlling device for electric motors, the combination with an electromagnetic winding, of a plunger adjustably mounted within said winding, a plurality of resistance switches carried by said plunger and arranged to be closed successively, certain of said switches being resiliently and adjustably supported thereon, a plurality of sections of starting resistance controlled by said switches, a stationary plug for sealing said plunger in its final position, a movable plug mounted within said winding for sealing said plunger in an intermediate position upon the closure of said switches, said winding being adapted to operate said plunger, to close said switches at predetermined speeds of the motor.
14. In a controlling device for electric motors, the combination with an electromagnetic winding, of a plunger mounted therein, a plurality of resistance switches carried by said plunger and arranged to be closed successively, a plurality of sections of starting resistance controlled by said switches, other switches carried by said plunger, and arranged to be operated successively, other sections of resistance controlled by said latter switches, said winding being adapted to operate said plunger to close said resistance switches successively at predetermined speeds of the motor and to simultaneously operate the last mentioned switches to insert a section of said last mentioned resistance in circuit with said winding upon the closure of each of said resistance switches.

In witness whereof, I have hereunto subscribed my name in the presence of two witnesses.

ALBERT J. HORTON.
